CLAIM

The ornamental design for a wireless charge bracket, as shown and described.

DESCRIPTION

FIG. 1 is a front perspective view of a wireless charge bracket showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a rear perspective view thereof, illustrating the wireless charge bracket of FIG. 2 in an alternate environment of use; and,

FIG. 10 is a rear perspective view thereof, illustrating the wireless charge bracket of FIG. 2 in another alternate environment of use.

The broken lines shown in the drawings are for the purpose of illustrating environmental structure or portions of the wireless charge bracket which form no part of the claimed design.

1 Claim, 10 Drawing Sheets
